UNITED STATES PATENT OFFICE.

GEORGE W. LEPPER, OF ST. ALBANS, VERMONT.

CULTIVATOR.

SPECIFICATION forming part of Letters Patent No. 324,265, dated August 11, 1885.

Application filed October 30, 1884. (No model.)

To all whom it may concern:

Be it known that I, GEORGE W. LEPPER, a citizen of the United States, residing at St. Albans, in the county of Franklin and State 5 of Vermont, have invented certain new and useful Improvements in Cultivators; and I do declare the following to be a full, clear, and exact description of the invention, such as will enable others skilled in the art to which it applies 10 to make and use the same, reference being had to the accompanying drawings, and to letters or figures of reference marked thereon, which form a part of this specification.

Figure 1 of the drawings is a side view of 15 my device with one wheel removed, and Fig. 2 is a rear view of the same. Fig. 3 is an inverted plan view, and Fig. 4 is a longitudinal central sectional view.

This invention has relation to improvements 20 in cultivators; and it consists in the construction and novel arrangement of devices, as will be hereinafter more fully set forth, and particularly pointed out in the claims appended.

Referring to the accompanying drawings by 25 letter, A indicates the main frame, to the under side of which is transversely arranged in suitable bearings the axle B, carrying ordinary driving and supporting wheels.

E indicates the cultivator-beams, which extend 30 forwardly and are journaled at their rear ends on the axle B. These beams E are peculiarly constructed at their outer ends, having an outwardly, downwardly, and forwardly curved portion, a, which is provided with a 35 concave face to seat the point i, which is held thereto, and may be properly adjusted by means of a screw passing vertically through the same. The standards or beams E are provided at the forward end of the curved portion a with a perforated depending lug b', in 40 which and an eyebolt, c', at the opposite end of the said curved portion a, is journaled the forward end of the blade f', whereby the same may be adjusted laterally by devices which 45 will be hereinafter explained.

J indicates the roller-arms, which are secured at their rear ends to the beams E, at or about the connection with the branch arms. These roller-arms curve upwardly and extend 50 forward slightly in advance of the plow-points, and are provided at their outer ends with a

vertical series of transverse perforations for the reception of a stud or spindle which supports the said rollers. From about midway the length of the beam E depends a hanger 55 lug, d, which is provided at its lower end with a perforation, as shown, for the passage of a horizontal transversely-curved rod D', the opposite end of which is curved upwardly and secured to the brace or branch arm e' of the 60 beam E.

F' indicates a vertical rod, which is secured at its lower end to the rear portion of the plow-blades, and is adjustably connected with the transversely-curved rod D', by means of a 65 socket, G, which is also adapted to be adjusted on the said curved rod. Therefore it will be seen that both a lateral and vertical adjustment of the blades may be had upon the curved rod D', there being set-screws employed 70 to fix the position of the socket with relation to the vertical shovel-rod and transversely-curved rod, respectively.

C indicates a transverse shaft which is journaled in bearings c c upon the upper side of 75 the frame A. This shaft C has keyed at one end a segment, H, and loosely arranged upon its opposite end a segment, I. The segments are provided at their outer edges or peripheries with an annular groove, and secured to 80 the forward upper end of these flanged portions are chains h', which lie in the said groove and are respectively connected at their lower ends to the beams E. The segment I is provided with a central vertical extension, h, having at its upper end a notch, h', for the engagement of a gravitating pawl upon the hand-lever K, as will be presently explained.

g is a collar which is keyed to the shaft C on the inner side of the hand-lever K, and is provided with a vertical extension and notch, 90 similar to that of the segment I, which is also designed to receive a gravitating pawl, k', pivoted to the hand-lever. These gravitating pawls k k', which are pivoted on opposite sides 95 near the lower end of the lever K, are respectively connected by wires k' to angle-levers M', which are also pivoted to the upper end of the said hand-lever. The hand-lever K is loosely arranged upon the shaft C between the segment I and keyed collar g, and is provided with a spring-hook, L, on its rear longitudinal

side, which is adapted to engage a hook-lug, M, upon the main frame when thrown rearward and downward by the driver. This pivoted spring-hook L is connected by means of 5 a rod, l, to a finger-lever, N, which is pivoted near the upper end of the hand-lever K. The upper end of the hand-lever K is provided with a pivoted or swiveled tip, P, having diametrically-arranged lateral studs, which are 10 adapted to engage the branches of the pivoted angle-levers M', and through the medium of the rods l² raise the gravitating pawls from engagement with the notches of the segment I and collar-lug keyed to the shaft C. Thus it 15 will be perceived that the plows may be raised together, or either of them raised independently, by the movement of the hand-lever, and the said lever locked to the hook-lug on the main frame, the pawls being at all times ready 20 to engage the notches on the said segment and collar-lug keyed to the shaft C, the pawls being disengaged from the collar-lug or segment by turning the swiveled tip P so as to bring the desired lateral pin inengagement with the 25 desired angle-lever, so as to lift its attached pawl.

The segments may have a stop, such as n', and the hand-lever a stop, such as m', whereby the movements of the respective devices may 30 be limited.

Having described this invention, what I claim as new, and desire to secure by Letters Patent, is—

1. In a cultivator, the combination, with the 35 beams, of the shovels pivoted at their forward ends, and provided with the vertical rod near their opposite ends, the transversely-curved rod, and the socket carrying set-screws, whereby the said shovels may be both vertically 40 and laterally adjusted, substantially as specified.

2. The combination, with the main frame and its axle, of the shovel beams or arms journaled thereon, the transverse shaft C, the segments at opposite ends thereof, the collar-lug 45 keyed to the said shaft, and the hand-lever

having devices adapted to engage the adjacent segment and collar-lug, whereby either or both of the shovel-arms may be raised, substantially as specified. 50

3. The combination, with the main frame, its axle and plow-beams, of the segments and chains connecting the same with the said beams, the transverse shaft, hand-lever having pawls adapted to engage the loose segment 55 and keyed collar-lug independently and alternately or simultaneously to raise the plows in a similar manner, substantially as specified.

4. The combination, with the transverse shaft having at one end a loose segment and 60 at the opposite end a fixed segment connected, respectively, with the plow arms or beams, of the collar-lug keyed on the said shaft, and the hand-lever having pawls to engage the loose segment and collar-lug, and a spring-actuated 65 pivoted hook to engage a hook-lug on the main frame, whereby both or either of the plows may be secured in a raised position, substantially as specified.

5. The combination, with the transverse 70 shaft, of the hand-lever arranged loosely thereon, the pawls on the opposite lower sides of the said lever, the angle-levers pivoted above the wires connecting the pawls with the angle-levers, and the swiveled tip having lateral 75 studs adapted to engage the said angle-levers alternately, substantially as specified.

6. In a cultivator, the combination, with the axle, of the shovel arms or beams having the inwardly and rearwardly directed brace- 80 arms, and the outer curved portion, a, having the concave face to seat the point i, and the roller-carrying arm secured to the said beam, and curved upwardly and forwardly in advance of the plow-point, substantially as shown 85 and described.

In testimony whereof I affix my signature in presence of two witnesses.

GEORGE W. LEPPER.
